(57) **CLAIM**

The ornamental design for a wearable medical data collection apparatus for collecting ECG data, as shown and described.

DESCRIPTION

FIG. 1 is a front view of the wearable medical data collection apparatus for collecting ECG data.

FIG. 2 is a back view of the wearable medical data collection apparatus for collecting ECG data.

FIG. 3 is a right side view of the wearable medical data collection apparatus for collecting ECG data.

FIG. 4 is a left side view of the wearable medical data collection apparatus for collecting ECG data.

FIG. 5 is a top view of the wearable medical data collection apparatus for collecting ECG data.

FIG. 6 is a bottom view of the wearable medical data collection apparatus for collecting ECG data; and,

FIG. 7 is a front perspective view of the wearable medical data collection apparatus for collecting ECG data.

The broken lines in the drawing views are included for the purposes of illustrating portions of the wearable medical data collection apparatus for collecting ECG data that form no part of the claimed design.
